VENTILATED SHIPPING CONTAINER FOR
FRUITS AND VEGETABLES

Mark B. Royce, Hohokus, N.J., assignor to Continental Can Company, Inc., New York, N.Y., a corporation of New York

Filed Dec. 12, 1956, Ser. No. 627,812

1 Claim. (Cl. 217—42)

The invention relates to a ventilated shipping container for fruits and vegetables, including an improved system for combining fiberboard and wood in the construction of such a container.

Definition

In the paper box business, shipping containers are commonly considered as falling into two broad classifications known, respectively, as corrugated containers and fiberboard containers. However, either term is occasionally employed in a generic sense as including the other. For simplicity, in this specification and in the appended claims, the term "fiberboard" will be used generically as including corrugated paperboard and all of the fiberboard or paperboard materials commonly used in the manufacture of shipping containers in the paper box business.

Summary

Heretofore, in combining the use of fiberboard and wood in making shipping containers, pieces of wood have been used as stiffeners in framing the container. Such wood pieces frequently form the ends of the containers or frames for ends covered with fiberboard. Sometimes solid wood ends or sides, or both, are wrapped inside folds of the fiberboard, or separate stiffening slats are stapled to the fiberboard. In contradistinction to such constructions, my container incorporates, as side walls, unitary wood slatted structures having wood slats secured in spaced relationship upon wood stringers. A further distinguishing feature of my container is that these side walls are unattached to the fiberboard part of the container and remain so even after the container has been filled and is ready for shipment. Thus, in its general arrangement, my improved shipping container comprises a bottom, top and ends formed of fiberboard, and sides formed of unattached unitary wood slatted structures. The fiberboard bottom, top and ends have narrow marginal flaps along their edges folded upwardly from the bottom, downwardly from the top, and inwardly from the ends and secured to one another, as by metal staples, to form continuous marginal flanges overlapping the peripheries of the wood slatted structures. The latter are unattached to the fiberboard part of the container and are held in positions adjacent the flanges by pressure of the contents of the container.

The four fiberboard panels which constitute the bottom, top and ends of the container, are connected end to end to form a continuous band. The marginal flaps along one of the side edges of the panels are folded over and stapled at the corners to form a continuous flange at that side edge of the band. The band is then rested on its side with this continuous flange down, and one of the wood slatted structures is then placed against the inside of the flange. After this the container is filled and the second wood slatted structure is placed over the contents. Finally, a continuous flange is formed at the other side of the band (which at this point is the upper side) by folding over the narrow marginal flaps and stapling

2

them together at the corners, and the container then turned over onto its bottom so that the contents come to bear against the wood slatted structures to hold them against the flanges and thus form the sides of the container.

Description

In the drawing, which shows the best mode contemplated by me for carrying out my invention:

Fig. 1 is a face view of the fiberboard blank from which is formed the bottom, top and ends of my container.

Fig. 2 is a face, or side elevational, view of one of the unitary wood slatted structures used in forming the sides of the container.

Fig. 3 is a top perspective view of the fiberboard band forming the bottom, top and sides of the container with the flanges at one of the edges of the band folded over and stapled together at the corners to form a continuous flange, this structure being shown turned over on its side ready to receive one of the slatted structures of Fig. 2 preliminary to loading of the container.

Fig. 4 is a vertical cross sectional view of the container structure of Fig. 3 after insertion of one of the wood slatted structures 11, and ready for loading.

Fig. 5 is a cross sectional view similar to Fig. 4 illustrating the succeeding steps of inserting the second wood slatted structure and folding over and stapling of the marginal flaps 15 at the second side of the container.

Fig. 6 is a perspective view of the loaded container ready to be turned over on its bottom so that the contents will hold the wood slatted sides in place against the marginal flanges of the fiberboard part of the container.

According to my invention there is provided a ventilated shipping container for fruits and vegetables comprising four fiberboard panels connected end to end to form a continuous fiberboard band, namely bottom panel 7, top panel 8, and end panels 9 and 10. These panels, and the continuous fiberboard band they form, have narrow marginal flaps 15 along their edges. In making the blank of Fig. 1 into the container band, ready to be shipped in flat folded form to the packer, panels 8 and 9 are folded over against panels 10 and 7, and the free edges of panels 8 and 9 are then fastened together in any suitable manner as by means of adhesive tape. This flat folded fiberboard band is then shipped to the packer along with the unitary wood slatted structures that are to form the sides of the container.

One of the wood slatted structures 11 which form the sides of my container, is shown separately in Fig. 2. It consists of wood slats 12 secured in spaced relationship upon wood "liners," or stringers, 13. (In the language of the box maker, this unitary wood slatted structure 11 is called a "veneer" panel.)

In setting up and packing the container, the continuous fiberboard band is first erected into the form shown in Fig. 3, the flanges 15 at one side of the band being folded over at right angles to the respective top, bottom and ends, and staped together where they overlap at the corners, as by means of metal staples 16. This forms a continuous marginal flange at the one side of the fiberboard part of the container. With this structure resting in a position in which this continuous flange is down, one of the veneer side panels is dropped inside the band and comes to rest against the flange. We now have the structure illustrated in Fig. 4. After the container has been loaded, a second veneer side panel is placed on top of the contents, and the flanges 15 at the second side of the container (the side which is then uppermost) are folded over and staped, as at 16, resulting in the structure illustrated in Figs. 5 and 6. Finally, the container is turned over onto its bottom 7 as indicated by the

arrow *a* in Fig. 6, so that the contents come to bear against the wood slatted structures, or veneer panels, to hold them against the flanges 11, and thus form the sides of the container. I have found that even though these sides are not fastened in any way to the fiberboard part of the container, nevertheless the coaction between the pressure of the contents and the restraining flanges which overlap the peripheries of the veneer panels, is such as to hold the veneer panels normal to the top and bottom of the container so as to form effective, and strong, columns to sustain loads imposed when my containers are stacked upon one another for shipment in trucks, freight cars or other carriers.

In the packing of the containers, I have found, for example, that when the contents are string beans, the second veneer side panel resting on top of the produce, either drops down, or can be depressed sufficiently, to permit insertion of the lower arm of a conventional stapling machine to apply the corner staples 16 previously described. Yet when the container is put over on its bottom, the beans shuck down so as to press both veneer panels tightly against the marginal flanges of the fiberboard top, bottom and ends.

The terms and expressions which I have employed are used in a descriptive and not a limiting sense, and I have no intention of excluding such equivalents of the invention described, or of portions thereof, as fall within the scope of the claim.

I claim:

A ventilated package for perishable articles which substantially fill a shipping container, said container comprising a rectangular fiberboard unit having four side

panels, each side panel having a marginal flap at each end which is substantially coextensive with its related side panel wherein the adjacent corners of said flaps overlap when folded into a substantially planar position, said 5 marginal flaps being of such a width that when in said planar position they only partially close the respective end of the container, each end further including a slatted unit having dimensions substantially the same as the cross-sectional dimension of said container, the slats in said 10 slatted unit being in spaced relation, and means securing the overlapped corners together at both ends, each end of the container having one slatted unit loosely contacting the inner faces of the respective marginal flaps and forming closures for the container ends, each slatted unit 15 being held in contact with its respective marginal flaps by said perishable articles within the container.
